UNITED STATES PATENT OFFICE.

BURTON BLACK, OF ORCUTT, CALIFORNIA.

PUMP.

980,050.

Specification of Letters Patent. Patented Dec. 27, 1910.

Application filed November 24, 1908. Serial No. 464,230.

To all whom it may concern:

Be it known that I, BURTON BLACK, a citizen of the United States, residing at Orcutt, in the county of Santa Barbara and State of California, have invented new and useful Improvements in Pumps, of which the following is a specification.

The invention relates to an improvement in pumps, being more particularly directed 10 to a pump for oil and water wells.

The main object of the present invention is the provision of a pump structure in which the material delivered therefrom is forced upwardly between the well casing and the 15 piston barrel instead of through the piston and barrel as in the usual construction.

Another object of the invention is the provision of a construction whereby a fluid under pressure can be delivered to assist the 20 operative stroke of the plunger.

Another object of the invention is the provision of means whereby a cleansing fluid admitted through the plunger barrel and below the plunger can be directed through the 25 check valves to thoroughly cleanse them of adhering grit, sand, or the like.

The invention will be described in the following specification, reference being had particularly to the accompanying drawings, 30 in which:—

Figure 1 is a longitudinal sectional view, illustrating the novel features of my invention. Fig. 2 is a similar view taken on a line at right angles to the line of section of 35 Fig. 1. Fig. 3 is a vertical sectional view of what I term the valve sleeve. Fig. 4 is a similar view on a line at right angles to the line of section of Fig. 3. Fig. 5 is a section on line 5—5 of Fig. 3. Fig. 6 is a section on 40 line 6—6 of Fig. 3. Fig. 7 is an enlarged vertical section of one of the valve cages. Fig. 8 is a top plan view of what I term the standing valve body.

Referring particularly to the accompanying drawings, my improved pump, as designed for use in connection with oil wells or the like, is adapted to operate within the well casing 1, and to be mainly carried by the plunger barrel 2, both of which parts are 50 of any usual or preferred construction. As is understood the plunger barrel in wells as at present constructed is fitted within the well casing and, by virtue of the different respective diameters of the barrel and cas-

ing, a considerable free space surrounds the 55 barrel.

In the usual type of well a plunger or piston operates within the barrel in which plunger there is arranged inlet and check valves for the passage of the material, it being understood that as the plunger descends the material passes through the same and collects in the barrel above the plunger, being lifted for discharge in the upstroke of the plunger. Under these conditions the 60 material is, of course, compelled to pass through the valves which are smaller than the surface area of the piston and, therefore, the piston does not descend freely. As a consequence the rod couplings securing the 65 sections of the piston rod together are forced into more or less close contact with the wall of the barrel and, owing to the comparatively large percentage of grit, sand, and gravel in the material being pumped, the 70 contact on the rod couplings and barrel quickly wears the parts to a condition in which they are of little use. The present invention is designed to entirely obviate these 75 objections by utilizing a solid plunger, or in other words one without valves of any kind, and to pump the material from the well 80 through that portion of the casing arranged beyond the plunger barrel, and not in the slightest degree through the latter.

In carrying out the preferred form of details of the present invention I provide what I term a valve sleeve 3, which is designed to be secured to the plunger barrel and during 85 operation be fixed with relation to the casing. The sleeve is of peculiar construction, being cylindrical at the lower portion, as at 4, and of an exterior diameter to fit more or less snugly the interior diameter of the casing 1. The cylindrical portion is approximately one-third the height of the sleeve 90 and is closed by a transverse partition 5 in which are formed a series of diametrically opposed circular openings 6 and a series of diametrically opposed outlets 7, the latter 95 being of triangular shape and located on a line at right angles to the line of the opening 6. Above the partition 5 the sleeve is continued in the form of tube-like projections 8, which conform in sectional dimension with 100 the respective openings 7 in the partition, said tubes rising vertically from the partition in alignment with the openings. The 105

2 tubes 8 are connected at their inner edges by a partition 9, which partition extends upwardly from the partition 5 and terminates below the relatively upper end of the sleeve, 5 so that at said point the upper ends of the tubes 8 communicate to provide a chamber 10. That portion of the sleeve above the openings 6 is thus free of an outer encircling wall, being divided, however, into two distinct spaces 10 by the partition 9. As the partition 9 terminates below the upper end of the valve sleeve it will be obvious, particularly from Fig. 1, that the chamber included within the circular portion of the sleeve below the partition 15 5 is in communication with the chamber 10 by two distinct tube-like passages 8 and is also in communication with the space between the casing 1 and the valve sleeve through two distinct openings 6.

20 The upper end of the valve sleeve is internally threaded, as at 11, and is of a size to engage the exteriorly threaded lower end 12 of the plunger barrel 2. The lower end of the valve sleeve, or more properly the 25 lower end of the circular portion 4 is internally threaded at 13 to receive what I term a valve body 14. The valve body 14 for a portion of its length near the upper end, as at 15, is of an exterior diameter 30 corresponding to the similar dimension of the circular portion of the valve sleeve, being, however, above said portion 15 circumferentially reduced to provide an annular projection 16 exteriorly threaded to fit within 35 in the threaded portion 13 of the sleeve. Below the portion 15 the valve body is circumferentially reduced throughout its length, as at 17, for a purpose which will presently appear.

40 As shown more particularly in Fig. 8, the upper end of the valve body is closed by a partition or plate 18 formed with a pair of diametrically opposed interiorly threaded openings 19, and the valve body when secured in place in the sleeve is so arranged 45 that the respective openings 19 align with the tube-like passages 8, or in other words the openings 19 are disposed directly below the openings 7 in the partition 5, as is more 50 particularly shown in Fig. 1.

To provide for securing the operative parts in applied position within the casing 1 I arrange at the appropriate point of said casing a coupling collar 20 interiorly threaded 55 at opposing ends to receive the respective ends of the casing sections, and so connect the sections as to form a continuous casing. Intermediate the sections, however, the collar is thickened, as at 21, which thickened 60 portion in the upper part terminates with its inner surface in alignment with the inner surface of the casing in the lower part, as at 22, and extends inwardly beyond the normally inner surface of the casing, providing 65 thereby a shoulder 23, which preferably in-

clines in a downward and inward direction, as clearly shown in Fig. 2. The valve sleeve and connected body are designed to have a direct bearing upon the coupling collar, and to provide the airtight connection necessary 70 at this point I arrange about the reduced portion 17 of the body a series of packing rings 24 and below and in contact with the lowermost ring I arrange a metallic packing ring 25. Below the packing ring 25 is 75 arranged a jam nut 26 having threaded connection with the lower end of the valve body and designed to exert a pressure upon the packing ring 25 with the effect to spread the rings 24. The lower surface of the ring 25 is 80 formed on its outer edge with an inclined portion to coöperate with the inclined shoulder 23 of the coupling collar, so that with the parts properly applied the packing ring 25 bears squarely upon the shoulder 85 23 of the coupling collar and the packing elements 24 above said ring engage the inner surface of the collar with the effect to provide an airtight juncture.

In connection with the openings 6 and 19, 90 which, for the purpose of the invention are identical in size and shape, I use valve members of identical construction. Each of said members comprises a cage 27 formed with suitable outlets, as 28, and interiorly threaded at the lower end, as at 29, the interior diameter of the cage exceeding that of the opening with which it is to be connected.

Secured within the cage is a bushing 30, having the upper portion threaded to fit 100 within the threaded portion 29 of the cage, and the lower portion circumferentially reduced and threaded, as at 31', to fit within the threaded openings 6 or 19. A valve seat 31 comprising a sleeve-like body formed at 105 opposing ends with a ground valve engaging surface, as 32, is secured within the cage, being centrally provided with an exterior laterally projecting flange 33, which is designed to engage beneath a shoulder 34 110 formed interiorly of the cage immediately above the threaded portion 29 and the upper end of the bushing 30, that portion of the valve seat projecting below the flange being normally seated in a reduced portion 35 115 formed in the bushing. It will thus be apparent that the valve seat is secured in place in a manner to permit its convenient removal when desired, and that the remaining parts are also arranged for convenient connection and disconnection. A valve 36 of the ball type is arranged in each cage to co- 120 operate with the valve seat therein, being disposed above the seat so as to close by pressure from above and open by pressure from beneath.

As has been previously stated the respective openings 6 and 19 are each provided with one of the valve members so that each of said openings is open to the free upward 130

travel of the material but closed against the downward travel thereof. Owing to the previously described arrangement of the openings 6 and 19, it will be obvious that a 5 pair of valve members, those connected with the openings 19, are arranged within the circular portion 4 of the valve sleeve below the plate 5, while a pair of said members are arranged above the plate 5 on each side of 10 the partition 9, in communication, of course, with the openings 6.

As thus constructed and arranged the operation of the improved pump is as follows: On the initial or upstroke of the plunger 15 the material from below the pump is drawn upward through the valves closing the openings 19 and on upward through the tube-like passages 8 into the chamber 10 and thence to the plunger barrel 2. During this up- 20 ward movement of the plunger there is no material passing through the valve members closing the openings 6, as it will be obvious that said openings are beyond the suction created by the plunger. As a matter of fact 25 the pull of the plunger is exerted to close the valves guarding the openings 6. Upon the downstroke of the plunger the material accumulated below the same, in the chamber 10 and passages 8, is forced downwardly. 30 This movement immediately closes the valves guarding the openings 19, and as the material must have an outlet it will immediately rise past the valve guarding the openings 6 and out through the cages of said valves into 35 the space between the valve sleeve and casing, finding its way in a continued pumping operation up between the casing and plunger barrel.

By reason of the fact that a solid plunger 40 is used within the barrel 2 I am enabled to utilize the space normally above the plunger as a receptacle for water or gas under pressure to aid the operative or downward movement of the plunger, thereby facilitating the 45 free and constant flow of the material from the casing. By reason of the arrangement described I am enabled to gain an additional advantage in that by allowing water or the like to accumulate or flow beneath the plunger, I can by a simple downward movement 50 of the plunger effectively flush and cleanse the check valves controlling the openings 6, as said cleansing fluid will be forced past and through said valves. By this means the 55 effectiveness of the pump is increased as it will be appreciated that in the case of the valves closing the openings 19, and herein- 60 after termed the inlet valves, the entire downward pressure of the plunger is utilized as a valve closing force while in the outlet check valves the pressure of the fluid above them between the casing and barrel is the primary closing means.

Having thus described the invention what is claimed as new, is:—

1. A valve sleeve for use in pumps including a body formed at one end to provide a circular portion closed at the upper end by a plate, said plate being formed with pairs of diametrically opposed openings, the sleeve 70 above the plate being formed with vertically extending oppositely disposed semi-circular sections, said sections coinciding at their central portions and having their free terminals connected by walls coincident with the periphery of the plate whereby to form opposing tubes in communication with one pair of openings, and valves removably mounted in the opposing pairs of openings and beyond the semi-circular section, where- 80 by to permit access to the valves from beyond the tubes.

2. A valve sleeve for use in pumps including a body formed at one end to provide a circular portion closed at the upper end by a plate, said plate being formed with pairs of diametrically opposed openings, the sleeve above the plate being formed with vertically extending oppositely disposed semi-circular sections, said sections coinciding at their 90 central portions and having their free terminals connected by walls coincident with the periphery of the plate whereby to form opposing tubes in communication with one pair of openings, the vertically extending 95 semi-circular sections terminating at their upper ends below the upper end of the connecting walls, whereby to provide communica- 100 tion between the tubes, and valves removably mounted in the remaining pair of openings and beyond the semi-circular sections.

3. A valve sleeve for use in pumps formed to provide opposing vertically extending tubes communicating at their upper ends, and valves arranged in diametrically oppo- 105 site relation on the sections and wholly be- 110 yond the tube walls, and a circular member having threaded connection with the lower end of the sleeve and formed with valve pas- 115 sages, in combination with a pump casing made in sections, a connector between two adjacent sections said connection being formed with an annular projection of less interior diameter than the similar dimension of the casing, said circular member being circumferentially reduced above the said projection, and packing arranged in said re- 120 duced portion to bear upon the projection to secure an air-tight connection between the parts.

In testimony whereof I affix my signature in presence of two witnesses.

BURTON BLACK.
